ONE PIECE SPORT SHIRT

George Ranieri, Riverside, Conn., assignor to Wings
Boyswear, Inc., New York, N. Y., a corporation

Application May 7, 1958, Serial No. 50,790

Term of patent 14 years

(Cl. D3—25)

Fig. 1 is a front elevational view of a one piece sport shirt showing my new design; and

Fig. 2 is a rear elevational view thereof.

I claim:

The ornamental design for a one piece sport shirt, substantially as shown.
